UNITED STATES PATENT OFFICE.

ALBERT C. TURNER, OF SAN FRANCISCO, CALIFORNIA.

DESIGN FOR A BADGE.

42,116.

Specification for Design.

Patented Jan. 23, 1912.

Application filed July 20, 1911. Serial No. 639,665. Term of patent 3½ years.

To all whom it may concern:

Be it known that I, ALBERT CLINTON TURNER, a citizen of the United States, and a resident of San Francisco, in the county of San Francisco and State of California, have invented a new and original and ornamental Design for a Badge, of which the following is a specification, reference being had to the accompanying drawing, forming part thereof.

The figure is a plan view of the article, showing my new design.

I claim—

The ornamental design for a badge as shown.

ALBERT C. TURNER.

Witnesses:

FRED P. GORIN,
B. D. SMALLEY, Jr.
